(57) **CLAIM**

The ornamental design for a heated glove, as shown and described.

DESCRIPTION

FIG. 1 is a perspective view of a heated glove showing our new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof; and,

FIG. 8 is a perspective view of a heated glove illustrated to show the pocket opening in a partially open configuration. In the drawings, the broken lines represent stitching that is a part of the claimed design.
